UNITED STATES PATENT OFFICE.

ARTHUR C. JONES, OF SOUTH PITTSBURG, TENNESSEE, ASSIGNOR TO ALAN S. KELLY,
OF SOUTH PITTSBURG, TENNESSEE.

INSULATED STOVE-TOP ATTACHMENT.

Application filed November 1, 1926. Serial No. 145,524.

The present invention relates to improvements in insulated stove top attachments and has for an object to provide an insulated top for use on cooking stoves and ranges in which a large per cent of the heat that is radiated from the stove or range is conserved, the cost of fuel materially lessened and the kitchen or room in which the stove or range resides is kept cool.

Another object of the invention is to provide an improved insulated top attachment of the character above referred to in which the construction is simple and inexpensive and in which the attachment may be effected simply and quickly.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a top plan view of an improved top attachment constructed according to the present invention and showing the stove as indicated therebeneath;

Figure 2 is an end view of a stove or range having the improved attachment thereon with parts broken away;

Figure 3 is a cross-section taken on the line 3—3 in Figure 1;

Figure 4 is an enlarged fragmentary vertical section showing a corner of the range and the insulated top and its attachment; and,

Figure 5 is a perspective view of one of the insulated lids.

Referring more particularly to the drawings, 6 indicates a stove or range having the top 7 with the ledge 8 projecting therefrom and carrying at its outer end the downwardly-turned flange 9 which is spaced from the side vertical walls of the stove 6.

The top is provided with the usual openings or eyes 10 to which are applied the removable cast-iron stove lids 11.

The improved top attachment is adapted to be placed upon the top 7 of the stove 6 and to be secured in place by devices which cooperate with the ledge 8 and flange 9.

The top attachment is shown as constructed of upper and lower spaced walls 12 and 13, respectively, of sheet metal or other ap-

propriate material between which a packing 55 of heat-insulated material 14 is interposed. The upper and lower walls 12 and 13 are connected by the end walls 15 which confine the packing material in place and in the top attachment so formed are made openings intended to register with the eyes 10 of the range top 7 when the auxiliary top attachment is put in place. The openings in the top attachment are formed by the tapering walls 16 into which are received the insulated 60 lids shown in Figure 5. These lids are made of the upper and lower sheet metal or other walls 17 and 18 with the inverted frusto-conical side wall 19. The inclination of this side wall 19 is such as to cooperate with the inclination given the wall 16 of the opening into which the insulated lid is adapted to fit whereby to conserve the heat. The lids are provided with the handles 20 for convenience in removing and replacing the 70 same.

The top attachment is made to overhang the sides of the stove and to project beyond the ledge 8 and its flange 9. This is advantageous in extending the insulating area 80 whereby to prevent the natural tendency of the heat to rise, due to convection currents, as 80% to 90% of the heat radiated from the stove issues from the top thereof and this extension will be very effective to cut down 85 to a minimum this dissipated heat. The overhanging edges of the insulated top attachment are also advantageous in providing the securing clamps 21 which clamps are provided with openings registering with 90 similar vertical openings in the overhanging portions of the insulated top attachment whereby to receive therethrough the bolts or other fastenings 22 having the nuts 23 on the lower ends thereof to take against the lower portions of the clamps 21 whereby these clamps may be secured tightly in position.

Such clamps are provided with the hooks 24 adapted to enter beneath the ledges 8 and behind the flange 9 of the permanent 95 stove top. The clamps are also provided with vertical outer portions 25 extending in spaced relation from the hooks 24 and horizontally outward of the flange 9, there being a slot formed between the hook 24 and the vertical spaced part 25 of the clamp. The clamps thus bind upon opposite sides of the flange 9 beneath the ledge 8, against the 100 105

vertical wall of the stove as indicated at 26 and against a substantial area of the under surface of the overhanging portions of the insulated top. The top is thus effectively held upon the stove against any tilting or lateral creeping and the alignment is preserved between the stove openings and the openings of the top attachment. At the same time the rounded wall 27 of the hook 24 10 forms a relatively wide mouth 28 for the slot between the parts 24 and 25. This facilitates the pressing of the clamp in place and also guides the clamp to its proper position, facilitating the subsequent assembly of the bolts 15 22 and in general making it an easier task to properly place the attachment on the stove.

In Figure 3, one of the insulated lids is indicated as lifted in dotted lines and a pot 20 or other cooking vessel is represented at 29 as being placed in a vacated opening in the insulated top attachment. It will be clear from this Figure 3 that the base portion of the opening in the top attachment is greater 25 in diameter than the diameter of the eye 10 of the stove top beneath. In this way the bottom of the vessel 29 may rest upon the edge of the eye 10 and be supported by the permanent top 7 of the stove, thus 30 relieving the top attachment of any weight of the receptacle; but at the same time the side portions of the pot will rest against the inclined wall 16 of the insulated top attachment, thus preventing the rising of 35 the heat, flame and smoke.

In Figure 1, I have shown one of the insulated lids as comprising two concentric annular sections 30 and 31 and a small inner cover section 32. Handles 33, 34 and 40 45 35 are provided individually for the sections whereby these sections may be independently lifted. For very small vessels, the cover 32 may be lifted to expose an opening of comparatively small diameter; 45 where the vessel is larger, the ring 31 may be lifted and the vessel set within the outer larger ring 30. The entire section or lid may be removed and the same is interchangeable with the other solid unit lids.

50 The improved attachment conserves the heat and consequently the fuel, keeps the room cool and prevents the heat from radiating up into the face and against the body of the attendant. The top of the attachment will not get very hot and consequently it is easy to keep clean. For this 55 reason it may be nickel-plated or enameled, which makes a very desirable finish on the top of a stove.

60 In cool weather the insulating caps may be removed where the room is to be heated from the stove.

In using the improved attachment all of the advantages of the old-style coal and

wood range are retained and only the undesirable features eliminated. 65

It will be obvious that many changes in the construction, combination and arrangement of parts could be made, which could be used without departing from the spirit 70 of my invention, and I do not mean to limit the invention to such details, except as particularly pointed out in the claims.

Having thus described my invention, what I claim and desire to secure by Letters Patent of the United States is:—

1. In combination with a range having a permanent top with eyes therein and an overhanging ledge and a down-turned flange, lids for the eyes, a removable insulated top attachment comprising upper and lower spaced walls, heat-insulating material therein and an outer wall connecting the inner and outer walls, said attachment having openings with inclined walls of greater diameter than the diameter of the eyes, said attachment having overhanging edges extending beyond said ledge and flange, and hook-shaped clamps removably secured beneath the overhanging portions and interlocking with said ledge and flange. 80 85 90

2. In combination with a range having a permanent top with eyes therein, a projecting ledge and downturned flange, an insulated top attachment having openings above the eyes and overhanging edge portions projecting beyond said ledge and flange, clamps removably secured beneath said overhanging portion and having hooks to engage beneath the ledge and within said flange, said hooks having curved portions, said clamps having vertical portions extending beneath said overhanging portions of the top attachment and spaced by slots from said hooks, said slots having wide upper mouths, said clamps adapted to fit against the sides of the stove, and means for removably securing said clamps to the overhanging portions of the top attachment. 100 105 110

3. In combination with a range having

a permanent top with eyes therein, a projecting ledge and down-turned flange, an insulated top attachment having openings above the eyes and overhanging edge portions projecting beyond said ledge and flange, slotted clamps having hooks to engage beneath said projecting ledge and within the down-turned flange, the slots receiving the down-turned flange, said clamps having inner walls engaging with the adjacent portion of the range, said clamps further having outer vertical portions adapted to lie in contact throughout a substantial area with the lower faces of the overhanging body portions of the attachment, and means for removably holding the clamps to the overhanging edge portions. 115 120 125

ARTHUR C. JONES.
